UNITED STATES PATENT OFFICE.

FRANK MUELLER, OF SCRANTON, PENNSYLVANIA, ASSIGNOR TO MUELLER ENGINEERING COMPANY, OF SCRANTON, PENNSYLVANIA, A CORPORATION OF PENNSYLVANIA.

HOOD CLAMP.

Application filed May 18, 1922. Serial No. 561,885.

To all whom it may concern:

Be it known that I, FRANK MUELLER, a citizen of the United States, residing at Scranton, in the county of Lackawanna and 5 State of Pennsylvania, have invented new and useful Improvements in Hood Clamps, of which the following is a specification.

This invention relates to automobile hood clamps, and has for one of its chief characteristics, the provision of a clamp designed to not only exert a downward pressure upon the hood, but to also cause a lateral pressure against the side of the hood, to hold it in its proper position, and to prevent relative 10 movement of the hood with respect to its support, which frequently results in squeaking or rattling noises.

In carrying out the invention, I make use of a barrel mounted for pivotal movement, 15 and in which barrel operates a spring pressed plunger which supports a pivoted handle, the latter being designed to engage a bracket secured to the side of the hood, and arrange the said handle, barrel, and 20 hinge in an eccentric alinement, to insure inward or lateral pressure against the hood, as well as a downward pressure thereon for the purpose above mentioned.

Another object of the invention resides in 25 providing the bracket and the handle with a seat of angular formation in cross section, which cooperates with the handle in a manner to prevent distortion of the entire clamp and the twisting and breaking of the plunger 30 under all circumstances.

The nature and advantages of the invention will be better understood when the following detailed description is read in connection with the accompanying drawing, the 35 invention residing in the construction, combination, and arrangement of parts as claimed.

In the drawing forming part of this application, like numerals of reference indicate 40 similar parts in the several views, and wherein:—

Figure 1 is a view in elevation of the hood clamp forming the subject matter of the invention, and showing it associated with the bracket adapted to be associated with the 45 hood of a motor operated vehicle.

Figure 2 is a view taken at a right angle to Figure 1.

Figure 3 is a detail view of the bracket above referred to. 55

Figure 4 is a detail view of the handle.

Figure 5 is a sectional view taken on line 5—5 of Figure 2.

Referring to the drawing in detail, A indicates generally the clamp forming the subject matter of the invention, and which clamp is designed for use in conjunction with hoods of automobile constructions. As illustrated, this clamp embodies a cylinder 10, the interior of which has a hexagon shape, although the exterior is preferably round. The cylinder is mounted for swinging movement upon a pivot 11, the latter being associated with spaced parallel lugs 12 rising from a base plate 13, and the latter is adapt- 60

ed to be secured to the frame of the vehicle (not shown) or any other appropriate part thereof. Slidable within the cylinder 10 is a plunger including a reduced threaded portion 15, and a larger portion 16 which is 65 preferably square in cross section, passing through a similarly shaped opening at the upper end of the cylinder to prevent rotation of the plunger. A nut 17 is threaded on the lower portion 15 of the plunger, and bearing 70 against this nut is the adjacent end of a spring 19 which surrounds the plunger and has its upper end bearing against the adjacent end of the cylinder 10. The plunger terminates at its upper end to provide a 75 forked extremity 20, between the portions of which is pivoted a handle 21, and the lower end of the handle which operates within the forked extremity is provided with a V-shaped notch 22. This handle is adapted to 80 engage a bracket which is adapted to be secured to the hood of the vehicle (not shown), and which bracket includes a plate 23 from which projects a web-like portion or flange 85

24. This web is shaped to provide an inclined edge 25 which terminates to provide a horizontally disposed edge portion 26, and the latter edge portion 26 is substantially of V-shaped formation in cross section to accommodate the notch 22 of the handle above referred to. A lip 27 rises from the bracket, and behind which the handle is arranged when the clamp is associated with the bracket, thus holding the handle from casual separation from the bracket as will be readily understood. It will be noted upon inspec- 90

100

105

tion of Figure 2, that the handle, barrel and hinge for the latter are arranged in an eccentric alinement when the clamp is in use, or in other words, associated with the bracket 5 above described, and by reason of this arrangement, a lateral pressure inwardly against the hood is provided in addition to a downward pressure upon the hood, with a view of holding the latter immovably arranged in its proper position. When the notch in the handle engages its correspondingly shaped seat 26, the forked extremity of the plunger is arranged or maintained in center, and the arrangement prevents any 10 distortion of the clamp in its entirety, or any twisting or breaking of the plunger which operates in the cylinder.

It will be noted that the spring 19 arranged within the barrel 10 can be easily adjusted to regulate its tension as the occasion may require, and all that is necessary to this end, is to remove the pin 11, separating the barrel from the base. This spring will then force the plunger downwardly, bringing the 25 reduced rounded portion within the squared opening in the upper end of the barrel, which permits the rod to be turned, while the hexagon nut 17 remains in the correspondingly shaped portion of the barrel 10, which 30 effects an adjustment of the nut for the purpose stated. After this adjustment, the barrel 10 is associated with the base and the pin 11 replaced in its position. An important feature of the invention hereinabove 35 described and clearly illustrated in the drawing, resides in the fact that the spring 19 cannot be casually or otherwise adjusted, either by the owner of the vehicle, or by mechanics or others who from time to time 40 must necessarily use the hood clamps. This is due to the fact that the barrel 10 must be wholly disassociated from the base 13 by first removing the bolt 11, inasmuch as the plunger cannot be moved downwardly to

bring the reduced rounded portion within 45 the squared opening of the upper end of the barrel for the purpose of adjusting the spring until the barrel has been wholly separated from the base.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:—

A hood clamp comprising a base, apertured lugs rising therefrom, a hollow member pivoted between said lugs, said member having a cylindrical outer surface and an angularly shaped inner surface and having a squared opening in the top thereof, a plunger slidable in said member and including spaced cylindrical portions and an intermediate squared portion to prevent turning of the plunger within the member, one of said cylindrical portions being threaded, an adjusting nut associated with said threaded portion and having a shape corresponding to the angular configuration of the interior of the member, the nut being held against rotation within the interior of said member, a spring surrounding the plunger and bearing against said nut and the upper end of said member, said spring being adjusted by the disconnection of said member from said base to permit the plunger to be depressed and rotated within the member but with respect to said nut, said rotation being effected by engagement of the other of said cylindrical portions of said plunger, within the squared opening of said member, a fork like terminal formed on the upper end of said plunger, and a handle pivoted on said fork.

In testimony whereof I affix my signature.
FRANK MUELLER.
